UNITED STATES PATENT OFFICE.

HENRY BUDDENHAGEN, OF TOLEDO, OHIO.

AUTOMATIC CUT-OFF FOR ENGINES.

SPECIFICATION forming part of Letters Patent No. 417,227, dated December 17, 1889.

Application filed August 22, 1889. Serial No. 321,637. (No model.)

To all whom it may concern:

Be it known that I, HENRY BUDDENHAGEN, a citizen of the United States, residing at Toledo, in the county of Lucas and State of Ohio, have invented certain new and useful Improvements in an Automatic Cut-Off for Steam-Engines; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to an automatic cut-off for steam-engines, and has relation to automatically controlling the stroke of the slide-valve, whereby to regulate the quantity of steam admitted to the cylinder.

20 The object of the invention is to render the reciprocation of the piston uniform and to effectually prevent the same from attaining too great speed.

The invention consists in the parts and combination of parts hereinafter described, and pointed out in the claims.

In the drawings, Figure 1 is a side elevation of an engine provided with my automatic cut-off with the plate to the steam-chest removed 30 to disclose the slide-valve and one of the ports. Fig. 2 is a side elevation of the opposite side of the steam-chest with the cylinder removed, and showing the inner side of the cut-off mechanism. Fig. 3 is a detail view showing the connection of the eccentric-rod and valve-stem with the cut-off mechanism, and also the connection of the ball-governor rod with the movable fulcrum of the bell-crank lever which effects the cut-off. Fig. 4 is a side elevation 35 of a portion of the engine, showing the slide-valve in a position to close both ports in the steam-chest by the centrifugal action of the governor. Fig. 5 is a plan view of the steam chest and cylinder with the upper portion of each removed, the slide-valve and piston being shown in full lines.

A designates the piston, which reciprocates in a cylinder B, receiving steam from the steam-chest C through ports E and E', respectively, and exhausting through a port F, the steam being admitted to the cylinder in front or rear of the piston-head by the reciproca-

tion of a slide-valve G, operated by an eccentric-rod G' in the usual manner. Eccentric-rod G' is connected with valve G in the following manner:

H designates a lever pivoted to the engine-bed at H' and extending upwardly above the eccentric-rod a short distance to allow of being formed in convenient shape at I to be 60 grasped by the operator.

J designates a bell-crank lever pivotally secured to the lever H at K, the upper end of the bell-crank lever being pivotally secured to a coupling-rod L, having a pivotal connection with the stem of valve G.

The eccentric-rod G' is formed with a notch G'', which engages with a projecting stud H'' upon lever H, whereby the reciprocation of said rod causes a forward and backward movement of the lever H upon pivot H'. The lower end of the bell-crank lever is provided with a rectangular stud M, which slides in a way N, formed in a plate O, secured upon a shaft O', which is secured in crank-arms P, attached 75 to the governor-rod R of a governor S.

In operation, steam being admitted to the steam-chest and the governor-balls being in their lowest position, a maximum amount of steam is admitted to the cylinder through 80 ports E and E', for the reason that the plate O, through the medium of the rod Q and crank-arms P, is inclined to cause the stud M of bell-crank lever J to travel in way O in substantially the same arc of a circle as the lever H 85 upon pivot H', thereby effecting the full movement of the slide-valve and admitting a full supply of steam to the cylinder in starting the engine. As soon, however, as the piston has attained the desired reciprocatory speed and 90 the governor-balls revolve at an angle of about twenty-five degrees from their pivotal connection the plate O is caused to assume a horizontal movement by means of the governor-rod and its connection with crank-arms P, thereby 95 causing the stud M of the bell-crank lever to move in coincidence with the horizontal way O, lessening the degree of oscillation of the same and causing the slide-valve to partially open the ports E and E', with the effect of allowing 100 a regular and normal stroke of the piston.

Should the engine attain too great speed by reason of any disconnection of the same with the machinery to which it may be attached

and the centrifugal throw of the governor-ball cause the same to assume a horizontal position, the downward movement of the rod Q will cause the plate O to assume an inclined position in inverse order to that described at the starting of the engine, thereby causing stud M to move in the way O in inverse order to the movement of the lever G' and lessening the stroke of the bell-crank lever to a degree 5 to shorten the strike-valve G sufficiently to cause the same to merely reciprocate upon the ports E and E', thereby closing the same and cutting off the steam from the cylinder with the effect of momentarily stopping the engine 10 until the governor-balls commence to descend, when the port E or E' is uncovered and steam admitted with the effect of starting the engine. 15

It will be seen that the device is automatic in its operation and that by means of the perforations 20 in the crank-arms P the rod Q can be coupled with the same to cause any desired lead to the slide-valve when the ball-governor is at any predetermined centrifugal throw to cause a normal speed to the engine 25 or to entirely cut off the steam from the cylinder.

What I claim is—

1. In an engine, a steam-chest, a slide-valve reciprocating therein and coupled with an oscillating lever, also connected with the eccentric-rod of the engine by means of a variable fulcrum-bearing in which one end of the oscillating lever moves, as and for the purpose set forth. 30

2. In an engine, an eccentric-rod, a slide- 35

valve, in combination with an oscillating bell-crank lever connected centrally to a pivotal lever and at one end with the slide-valve, the opposite end being connected with a variable bearing connected with the governor-rod, the eccentric-rod being connected with the pivoted lever, as and for the purpose set forth. 40

3. In an engine, a governor, a vertically-movable rod connected therewith, a shaft provided with a plate at one end having a way 45 formed therein, and crank-arms at the opposite end connected with the movable rod, in combination with a lever pivoted to the engine and having a connection with the eccentric-rod, and a bell-crank lever pivoted to said 50 lever, one end of which moves in said way, the opposite end being connected with the slide-valve of the engine, as and for the purpose set forth.

4. In an engine, a slide-valve pivotally connected with the governor by means of a bell-crank lever connected at one end with the slide-valve and at the opposite end with the movable way, and the crank-arms connected with the governor-rod and supporting said 55 movable way, substantially as shown and described.

In testimony that I claim the foregoing as my own I hereby affix my signature in presence of two witnesses.

HENRY BUDDENHAGEN.
